UNITED STATES PATENT OFFICE.

LOUIS L. DRIGGS, OF NEW YORK, N. Y.

COMBINATION PERCUSSION AND TIME FUSE.

1,311,792.

Specification of Letters Patent. Patented July 29, 1919.

Application filed January 2, 1917. Serial No. 140,183.

To all whom it may concern:

Be it known that I, LOUIS L. DRIGGS, a citizen of the United States, residing at New York, in the county of New York and State of New York, have invented certain new and useful Improvements in Combination Percussion and Time Fuses; and I do hereby declare the following to be a full, clear, and exact description of the invention, such as will enable others skilled in the art to which it appertains to make and use the same.

My invention relates to improvements in fuses for shells, and consists in providing an improved combination percussion and time fuse, especially adapted for use with projectiles which are intended to be fired from long ranges, such as howitzer shells or the like.

10 The invention is especially adapted for use with shells containing high explosives, such as picric acid or trinitrotoluol.

Such shells are usually provided with rather thin but strong walls containing a charge of high explosive. In order to detonate the charge something more powerful than the regular percussion fuse is necessary. Consequently the fuse is provided with a larger ignition charge, which is connected to one or more tubes containing gun cotton or trinitrotoluol, or other suitable explosive. In this tube or tubes are the explosives, which are first detonated, and causing the detonation of the high explosive charge.

5 My invention is especially intended to provide an absolutely safe combination time and percussion fuse, which cannot be prematurely exploded as from accidentally dropping the shell, or rough or careless handling thereof, and at the same time I provide an arrangement by which the locking means for normally holding the plunger in the safety position are held out of engagement with said plunger after the shell has acquired sufficient rotary velocity, such for instance as that imparted to it in passing through the bore of the gun.

My invention will be understood by reference to the accompanying drawings in which the same parts are indicated by the same reference symbols throughout the several views, and in which—

Figure 1 is a side elevation of the fuse complete;

Fig. 2 shows a section through the axis of the fuse and part of one of the adjacent

tubes for containing the ignition charge, parts of the shell being shown in dotted lines, and parts of the fuse being shown in elevation;

60 Fig. 3 is a perspective view showing the spring clip for holding the plunger in place;

Fig. 4 shows the automatic catch for holding the spring clip locked out of engagement with the plunger after the shell has acquired the rotary velocity due to being fired from the gun;

Fig. 5 is a front view of the plunger; and

Fig. 6 is a section through the plunger along the line 6—6 of Fig. 5.

A represents the fuse stock having the chambered portion 1 screwed into the gun in the usual way. Mounted in the forward portion of the chamber of the fuse stock is the primer block 2, chambered, at its forward portion, as at 3 to hold the charge 4 of quick burning powder, the rear end of which chamber is closed by the thin disk 5, of paraffined paper, or other suitable material, which disk masks the perforations 6 and 7 in the primer block. 8 represents the primer of the usual or any preferred construction.

In rear of the primer block 2 the fuse stock is provided with the cylindrical chamber 9, in which the body portion 10 of the plunger slides freely and longitudinally through a short distance. The plunger carries the firing point 11, and is provided with the rearwardly extending stem 12, flanged as at 13. The opposite sides of the plunger are provided with parallel grooves 14, adapted to receive the resilient arms of the spring clip, as will be hereinafter described, and the plunger is also provided with passages 15, extending outward at either side of the firing point 11, and opening interiorly into the axial bore 16 through the stem of the plunger; thus forming a Y-shaped channel for the passage through the plunger of the ignition charge from the primer 2 and the chamber 3.

The plunger is normally held in the safety position by the spring clip shown in Fig. 3, which comprises the central portion 17 connected to the primer block 2, and provided with an opening 18 for the passage therethrough of the firing point 11. Connected to this central portion are the resilient arms 19, each terminating in a weight 20, in the form of a segment of a cylinder, as shown most clearly in Fig. 3. These weights may

be integral with, or attached to the resilient arms 19, and normally grip the stem of the plunger holding it against forward movement.

- 5 When the shell is spun up, as in passing through the bore of the gun, these weights are thrown outward and, pressing back the resilient catches 21 on the ring 22, lock the spring clip in the distended position, leaving the plunger free to fly forward when the flight of the shell is suddenly arrested, as by striking the ground, the target, or any other solid object.
- 10 This arrangement provides a perfectly safe lock for the plunger, except after the shell has been spun up, and yet provides a positive lock to keep the spring clip out of engagement after the fuse has been primed automatically by firing the projectile from the gun.

When the plunger is in the safety position, shown in Fig. 2, these catches 21 project into notches 13^a in the flange 13 of the plunger.

- 15 In rear of the plunger I provide in the fuse stock the screw plug 23, which is preferably chambered in its forward portion and provided in the rear with a head 24, perforated as at 25 to permit the passage 30 of the flame from the igniter rearward. This opening may also be closed by a small disk 26, let into a groove 27.

- 20 This plug 23 is provided with sockets 28 so it may be conveniently screwed in place by means of a spanner. In rear of the screw plug 23 I provide a closed tube 30, screwed at its forward end into the shell as at 31. This tube contains an auxiliary priming charge not shown, which is ignited by the primer or by the time train.

- 25 The fuse stock projects forward beyond the nose of the shell, having a cylindrical stem 40, on which the time train rings B and B' are mounted, and is screw threaded at 41 to engage the cap C. The forward end of the fuse stock is provided with a cylindrical chamber 42, into which projects the block 43 carrying the primer for igniting the time train; into this block the 30 plunger 44 is screwed, and this plunger is locked to the primer block by means of the set screw 45. The forward end of the plunger is shouldered as at 46 to engage a corresponding shoulder on the cap C, and is thus held against outward movement, while it is normally held against inward movement by the split ring 47.

- 35 The cap C and the plunger 44 are perforated to admit the safety lock 48, which 40 consists of a bar projecting through the plunger and locking the same to the cap C. This safety lock prevents the accidental igniting of the priming train should the shell be dropped, or should it be handled 45 roughly.

Projecting into the chamber 42 is the anvil 49 having the firing point 50 adapted to engage the primer when the plunger 44 flies backward after the gun has been fired. The chamber 42 is connected by the passage 51 to the time train, the inner end of which is preferably closed by a paraffined paper disk 52.

In the passage contained in the time train ring B' are placed the pellets 53 connected 75 to the powder train 54. The powder train 54 is connected by the passage 55 in the ring B to the powder train 56. The powder train 56 is connected by the passage 57 to the powder in the passage 58, which is 80 closed by the plug 59.

The flange of the fuse stock is milled on its forward edge as at 60 to engage the felt disk 61 in rear of the paper ring 62, which closes the powder train 56. In a similar 85 way the front face of the ring B is milled as at 63 to engage the felt pad 64, which bears against the paper ring 65. By having a felt pad in rear of each of the rings a tight joint is secured without having the engaging 90 surface of metal against metal, which might tend to prematurely explode the time train; and moreover, the felt acts as a heat insulator to prevent the transmission of sufficient heat to the rear which might 95 cause the fuse to operate prematurely.

In order that the powder may burn uniformly, in the powder train, I provide passages 66 to permit the escape of the gas from the burning powder, which passages 1 are screened by the annular shoulder 67 on the cap C. This cap C is held against turning on the fuse stock by means of the set screw 68.

The operation of the device is as follows: 1
Just before loading the projectile in the gun, remove the safety lock 48.

When the gun is fired, the plunger 44 will be forced backward due to its own inertia, distending the split ring 47, and causing 1 the forward primer to strike the point 50. This will cause the charge in the forward primer to blow through the passage 51, blowing out the disk 52, and igniting the pellets 53, and the time train 54. The time train 1 will be set at the desired time in the usual way. I have shown the ring B as graduated to 31 seconds but any suitable time train may be used with the fuse, as desired.

After the time at which the train is set 1 has expired, the powder in the passage 58 will be ignited, which will ignite the powder charge 4 in the main primer, and the flame will blow to the rear through the plunger 10 igniting the priming charge in the tube 30, 1 and exploding the shell.

The foregoing explains the action of the fuse as a time fuse; the fuse will also act as a percussion fuse as follows:

As the projectile leaves the gun, it will 1

be spun up by the rifling, which will cause the weights 20 to fly out, due to centrifugal force, and this will press back the spring catches 21, allowing the weights to pass. 5
5 After passing beyond the catches 21, they will spring up and engage in the inner surface of the weights 20, and will hold the same in a distended position so that as the rotary motion of the shell is diminished, as 10
10 would occur when fired at long ranges, the weighted arms will still be held distended and the rim 13 of the plunger can freely pass forward between said weights. Thus when the shell is suddenly arrested, as when 15
15 striking the target or earth, this plunger 10 will fly forward igniting the primer 8, and exploding the shell as already described in connection with the time train arrangement.

It will be obvious that various modifications might be made in the herein described fuse, and in the construction, combination and arrangement of parts which might be used without departing from the spirit of my invention.

25 Having thus described my invention, what I claim and desire to secure by Letters Patent of the United States is:

1. The combination with a fuse stock, of a primer and an igniting charge carried in said fuse stock, a plunger mounted in said fuse stock and adapted to explode said primer, the said plunger being provided with a passage therethrough for the flame from the primer, a spring clip having 30
30 weighted resilient arms normally locking said plunger in the safety position but thrown out of engagement therewith when the shell is spun up, automatic means for locking said spring clip in the disengaged 35
35 position after it has been acted upon by centrifugal force, comprising inclined spring catches adapted to be pressed backward by said weighted arms as they are thrown outward by centrifugal force but to lock said 40
40 arms against returning inward when said centrifugal force decreases, due to the slowing down of the rotary motion of the projectile, and a time powder train mounted on the forward end of said fuse stock and connected to said igniting charge, substantially 45
45 as described.

2. The combination with a fuse stock, of a primer and an igniting charge carried in said fuse stock, a plunger mounted in said

fuse stock and adapted to explode said 55 primer, the said plunger being provided with a passage therethrough for the flame from the primer, a spring clip having weighted resilient arms normally locking said plunger in the safety position but thrown out of engagement therewith when the shell is spun up, automatic means for locking said spring clip in the disengaged position after it has been acted upon by centrifugal force, comprising a ring provided with inclined spring 60
60 catches projecting forwardly and at an angle and adapted to be pressed backward by said weighted arms as they are thrown outward by centrifugal force but to lock said arms against returning inward when said centrifugal force decreases, due to the slowing down of the rotary motion of the projectile, and a time powder train mounted on the forward end of said fuse stock and connected to said igniting charge, substantially 65
65 as described. 70
70

3. The combination with a fuse stock, of a primer carried in said fuse stock, a chamber located in front of said primer and containing powder adapted to be ignited by said 80
80 primer, a plunger adapted to explode said primer, the said plunger being provided with a body portion, a firing point, and a stem, with a channel through said body portion and stem for the passage rearward therethrough of the flame from said primer and powder chamber, the said passage through the plunger carrying the flame to the rearward into the shell, a spring clip having 85
85 weighted resilient arms normally locking 90
90 said plunger in the safety position but thrown out of engagement therewith when the shell is spun up, automatic means for locking said spring clip in the disengaged 95
95 position after it has been acted upon by centrifugal force, comprising inclined spring catches adapted to be pressed backward by said weighted arms as they are thrown outward by centrifugal force but to lock said arms against returning inward when said 100
100 centrifugal force decreases, due to the slowing down of the rotary motion of the projectile, and a time powder train mounted on the forward end of said fuse stock and connected to said igniting charge, substantially 105
105 as described.

In testimony whereof I affix my signature.
LOUIS L. DRIGGS.
